UNITED STATES PATENT OFFICE.

OSCAR A. NEITZEL AND HARRY N. HOLM, OF MINNEAPOLIS, MINNESOTA.

CONTROL FOR SWINGING DOORS, WINDOWS, AND THE LIKE.

Application filed December 24, 1925. Serial No. 77,547.

Our invention has for its object to provide an extremely simple and highly efficient control for holding swinging members where set in different positions, and it is especially adapted for holding swinging doors, windows and the like, and to this end it consists of the novel devices and combinations of devices hereinafter described and defined in the claim.

10 In the accompanying drawings, which illustrate the invention, like characters indicate like parts throughout the several views.

Referring to the drawings:

Fig. 1 is an elevation of a door frame and door hinged thereto with the invention applied to the door and its frame;

Fig. 2 is a view principally in horizontal section, taken on the line 2—2 of Fig. 1 with some parts shown in different positions by means of broken lines;

Fig. 3 is a side elevation of the invention;

Fig. 4 is a bottom plan view of the same;

Fig. 5 is a detail principally in section, taken on the line 5—5 of Fig. 4; and

Fig. 6 shows a modification of the rod.

The numeral 7 indicates a swinging door hinged to a door frame 8.

The control, as shown in Figs. 1 to 5, inclusive, comprises a horizontal swinging rod 9, two attaching brackets 10 and 11 secured by wood screws, the former to the door frame 8 and the latter to the door 7. One end of the rod 9 is bent vertically downward to afford a pivot stud 12 mounted in a bore in a hinge lug 13 on the bracket 10 and connects said rod to the door frame 8 for horizontal swinging movement. A cotter pin 14 inserted through a bore in the pivot stud 12 below its hinge lug 13 holds the rod 9 against removal from the bracket 10.

The other end of the rod 9 extends through a transverse bore in a vertical post 15, the lower end of which is reduced to afford a pivot stud 16 turnably mounted in a vertical bore formed in a lug 17 on the bracket 11 and connects said post to said bracket for swivel action. A cotter pin 18 inserted through the stud 16 below the lug 17 holds the post 15 against removal from the bracket 11. The post 15 is longitudi-

nally split at 19 through the axis of its transverse bore. For frictionally clamping the prongs of the post 15 onto the rod 9 under a variable and yielding friction, a thumb screw 20 having a knurled head is 55 loosely inserted through a bore in one of said prongs and has screw-threaded engagement with the other prong thereof. A coiled spring 21 encircling the thumb screw 20 is compressed between the apertured prong of 60 the post 15 and the knurled head on said screw. By adjusting the thumb screw to compress or release the spring 21, the frictional engagement between the rod 9 and the post 15 may be varied at will. This 65 frictional engagement between the rod 9 and post 15 is such that the door 7 will be held open where set in any desired position and the control is entirely automatic in its action so that the same does not have to be 70 moved or adjusted when swinging the door 7 open or closed. As the control does not have any direct engagement with the door or the floor over which it swings, said door 75 or floor will not be marred or injured.

Referring now to the detail shown in Fig. 6, it will be noted that the end portion of the rod 22 that is arranged to slide in the split post 15 is slightly tapered at 23 so that its frictional engagement with said post 80 is progressively increased during the initial opening movement of the door until said door extends at substantially right angles to its closed position and then the friction is the same during the balance of the opening 85 movement of the door. This form of rod is especially adapted for use on doors which are controlled by means of air checks. By the use of our improved control, a door or window may be swung substantially 180° 90 and automatically held in any of its intermediate positions.

What we claim is:

A control of the kind described comprising a pair of brackets one of which is applicable to a relatively fixed support and the other of which is applicable to a swinging member hinged to said support, a rod hinged to one of said brackets, a post swiveled to the other of said brackets and having a 100

transverse bore, said post being longitudinally split through said bore, a screw extending loosely through an aperture in one of the prongs of the split post and having screw-threaded engagement with the other prong thereof, and a coiled spring encircling the screw and compressed between the

apertured prong of the post and an abutment on said screw.

In testimony whereof we affix our signatures. 10

OSCAR A. NEITZEL.
HARRY N. HOLM.
